UNITED STATES PATENT OFFICE.

HARMON E. LINDBLADH, OF BOSTON, MASSACHUSETTS.

FEEDING APPARATUS.

1,258,026.

Specification of Letters Patent.

Patented Mar. 5, 1918.

Application filed June 25, 1913. Serial No. 775,737.

To all whom it may concern:

Be it known that I, HARMON E. LINDBLADH, a citizen of the United States, residing at Boston, in the county of Suffolk and 5 State of Massachusetts, have invented a new and useful Feeding Apparatus, of which the following is a specification.

In apparatus for successively advancing sheets of thin material from a pile, as paper-feeders, much difficulty is encountered, especially with rapidly operating devices, in obtaining an accurate delivery of single sheets. Pneumatic feeders are, at best, slow in action, and when the stock operated upon is 15 porous, the suction means is very liable to pick up a plurality of sheets. The well-known buckling type of feeders is erratic in this respect, varying the delivery for no apparent reason, and when the stock is highly 20 glazed they become inoperative, advancing sometimes one, sometimes two, or, again, many sheets with the same adjustment of elements. It is the purpose of this invention to provide means free from complication whereby the feeding shall be effected 25 quickly and with precision, and to generally improve the feeding apparatus.

In the accompanying drawings appears a single embodiment of the invention, Figure 30 1 being a top plan view thereof; Fig. 2 a front elevation, parts being broken away; Fig. 3 a side elevation looking from the left in Fig. 1; Fig. 4 an elevation of the opposite side of the machine, parts being omitted; Fig. 5 a front elevation of the advancing 35 mechanism; Fig. 6 a side elevation of the same; Fig. 7 an enlarged detail showing the indicating mechanism, and Figs. 8 and 9 enlarged details illustrating successive stages 40 of the feeding operation.

Similar characters designate like parts throughout the various figures of the drawings.

The reference characters 10, 10 are applied 45 to vertical standards which rise from a suitable base. Stepped in a bearing 11 at the bottom of each of these standards is a screw 12 engaging a correspondingly threaded opening in a lateral projection or lug 13 from a beam 14. This beam supports a table 15 adapted to receive a pile S of the sheets to be fed. Extending forwardly, or in the direction of advance of the work, from each of the standards 10 are supports 50 in the form of horizontal rods 16, 16, situated one above the other and free at their

forward ends. On each pair of these rods are blocks or carriers 17 and 18 adjustably secured on their supporting rods by set-screws 19. The blocks 17 and 18, respectively, have extending through openings in them transverse rods or supports 20 and 21, and on these rods midway between the standards are held blocks or carriers 23 and 24, respectively, by set-screws 25. The last-named blocks have mounted in them at their 60 upper portions an actuating rod 26, and below furnish bearings for a shaft 27. The rod 26 and shaft 27 are further supported at the rear by blocks or carriers 28 and 29, 65 respectively, adjustably fixed by set-screws 30 to transverse supporting rods 31 and 32; which are, in turn, removably mounted in pairs of brackets 33, 33 fixed to the rear side of the standards. 70

Secured to the extremity of the rod 26 is a bearing head 34, in which is splined for vertical reciprocation a presser-rod 35. The rod is further guided by a sleeve 36 having an arm 37 surrounding and positioned by 75 the shaft 27. At the bottom of the rod 35 is fixed a presser-foot 38 for retaining the sheets against forward movement, said presser-foot having a compound sheet-engaging face furnished by a block 39 of some 80 such yieldable material as rubber, and a forward rigid surface 40, which is preferably rough. The face 40 is formed upon, and the block 39 set in, a plate 41 sliding in ways at the sides of the presser-foot, and being adjustable therein to position the engaging 85 surfaces longitudinally of the apparatus by means of a screw 42 threaded through the rear of the presser-foot and swiveled into the adjacent edge of the plate 41. A lock-nut 43 serves to secure the screw and plate 90 at the desired point. The engaging surface of the presser-foot is forced against the sheets by a spring 44 having its upper end abutting against the sleeve 36, while its 95 lower end rests upon a collar 45 adjustably secured to the rod 35 by a screw 46. Upward or downward movement of the collar provides for an increase or diminution in the tension of the spring, and therefore the 100 force exerted by the presser-foot upon the sheets. The presser-foot is raised from the work by a cam 47, fast upon the rear extremity of the shaft 27 and co-operating with an anti-friction roll 48 journaled in the forked 105 extremity of a rod 49, which is mounted to slide through a pair of brackets 50, 50 pro-

jecting from the rod 35. The upper portion of the rod 49 is threaded, and carries a nut 51 contacting with the top of the upper bracket 50, for the purpose of varying the 5 position of the roll 48 with respect to the cam and thus the extent of lift of the presser-foot. The rod 49 is retained in its adjusted position by a set-screw 52 passing through the lower bracket 50 into engagement with the rod. In this lower bracket 10 the rod is splined to retain the roll in the proper relation to the cam.

The shaft 27 is rotated to actuate the cam 47 by a spiral gear 53, splined to the shaft 15 and retained in a definite position with relation to the apparatus between cheeks in the block 24 while allowing the shaft to move through it. Meshing with the gear 53 is a second spiral gear 54 fast upon a trans- 20 verse shaft 55 journaled at the bottom of the blocks 18, 18. This imparts rotation to mechanism for drawing the sheets from the retaining means or presser-foot. Two such mechanisms are furnished, these being sym- 25 metrically situated with respect to the longitudinal axis of the machine, and each having pairs of independent arms 56, 56 adapted to be fixed to the shaft by set-screws 57 which permit the angular relation of the 30 arms 56, 56 to be varied with respect to one another. Upon the outer ends of the arms 56 are fulcrumed levers 58 and 59 provided at their outer extremities with curved sheet-engaging faces 60 and 61, respectively. 35 The former I term a fanning member, because of its action in gradually advancing or jogging the sheets, and the face of this is smooth and rigid, being preferably of metal. The face 61 is upon a feeding member, and 40 is provided with a layer of some such yieldable material as rubber, which will give strong frictional effect. Both levers 58 and 59 are drawn against stops 62 projecting from the arms by springs 63, extending be- 45 tween eyes 64 projecting from the hubs of the arms and eye-bolts 65 passing through the ends of the levers opposite the shaft-engaging faces. Nuts 65^a threaded upon the eye-bolts outside the arms enable the opera- 50 tor to adjust the force with which the working faces bear against the sheets. The feeding face 61 is carried by a movable shoe 66 which may be held in two positions by a screw 67. In full lines in Fig. 6 is shown 55 the normal or feeding position, while in dotted lines in the same figure the shoe is illustrated as thrown back, thus rendering the feeding surface ineffective and allowing the fanning surface to act alone. When in 60 the last-named position the workman can cause the fanning member to impart to the pile of sheets a longitudinal displacement preliminary to the feeding of the first sheet, thus avoiding the necessity for inaccurately 65 performing the operation by hand.

The action of the cam 47 is so timed that the presser-foot is raised from contact with the pile of sheets (see particularly Fig. 8) as the sheet-advancing mechanism, rotated in the direction of the arrow, brings the 70 member 58 against the upper sheet of the pile. As the smooth metallic surface 60 of this member slides over the sheet, its frictional engagement therewith not only moves this sheet in the direction of feed, but also 75 certain of the sheets below, the extent of advance decreasing from the top downward. When the sheets have been thus fanned out, the member 60 passes on in its rotation from the top sheet (Fig. 8), and 80 the presser-foot is forced down by the spring 44 upon the edges of the jogged sheets. By a suitable adjustment of the spring 63 of the fanning member, and by varying the longitudinal relation of the en- 85 gaging surfaces of the presser-foot by the screw 42, the roughened surface 40 may be made to clear the top sheet of the pile and engage only the second sheet, while the flexible material 39 bears on the succeeding 90 edges of the sheets which have been displaced, it generally conforming to their incline. When all the sheets except the upper, and especially the second sheet which is most liable to improper delivery, are thus 95 firmly held, the yieldable surface 61 engages the upper sheet and thrusts it forward until it is seized by the rolls R, R which deliver directly to the machine fed. The timing of this operation may be controlled by the 100 angular adjustment of the feeding member with relation to the fanning member. The exact pressure for a positive advance of the upper sheet, without bringing too great tension upon sheets below which are re- 105 tained by the presser-foot, may be assured by an adjustment of spring 63 controlling the feed member.

The removability of the rods 31 and 32 permits the rod 26 and shaft 27 of the 110 presser-foot to be adjusted to any desired point over the feed-table, to provide for correct coöperation with sheets of different lengths, the blocks 17 and 18 being correspondingly adjusted to respectively provide 115 the necessary bearings for the elements 26 and 27 and to properly position the advancing mechanism.

Rotation is imparted to the shaft 55 by a gear 68, secured to it, and driven through 120 a large idler 69 from a gear 70 connected to some source of power. The short shafts of the gears 69 and 70 are supported upon one of the rods 16, which may be larger than its companions, by means of blocks 72 and 73 125 adjustably secured to the rod. From the block 72 depends a curved arm 74, having in it a segmental slot the center of which is located at the axis of the gear 69. The gear 68 is so fixed to the shaft 55 as to be 130

readily removable, and by changing the diameter of this gear and correspondingly adjusting the gear 69 along its slot the rate of rotation of the sheet-advancing mechanism 5 may be altered as desired.

Upon the shaft 55 fixed beside the gear 68 is a sprocket wheel 75, driving by a chain 76 a wheel 77 fast upon a shaft 78. This shaft is journaled in blocks 79 each adjustably secured by a set-screw to a rod 71 extending horizontally from the top of a standard 10. The shaft 78 has secured to it a crank-disk, the pin of which is joined by a rod 81 to a link 82 depending from the outer face of the standard 10. Pivoted at the bottom of the link is a pawl 83 coöperating with the teeth of a ratchet-wheel 84 fixed to a shaft 85 journaled in both the standards 10. Just inside the standards the shaft 85 carries a pair 20 of bevel-gears 86 meshing with corresponding gears 87 at the upper ends of the screws 12. It will be seen that as the ratchet is oscillated upon the link by the rotation of the crank-disk, it will advance the ratchet-wheel 25 step by step rotating the shaft 85, and through the bevel-gearing gradually turning the screws 12, thus raising the table 15 toward the sheet-engaging members.

As the elevating mechanism just described 30 imparts a regular movement to the table not dependent upon the character of the material fed, it would after a time, if thin stock were being handled, bring the top of the pile to a height at which an excessive pressure 35 would be exerted upon it by the advancing members. That is, the rate of table-elevation under such conditions is much greater than the rate at which the height of the pile is reduced. To regulate this I provide automatic means for temporarily arresting the 40 upward feed of the table. The pawl 83 has a long forwardly extending arm 88, with an inclined extremity 89 with which coöperates a roll 90 journaled upon a lever 91 fulcrumed between its ends on a bracket 92. Depending from the lever between the roll 45 and the fulcrum-point is a rod 93 positioned by a pair of nuts 94, 94 threaded upon the rod at opposite sides of the lever. Journaled at the 50 bottom of the rod is a roll 95 which is allowed to float lightly upon the upper sheet of the pile or in proximity to the line of feed, its pressure being controlled by a counter-weight 96 movable upon the arm of the lever 91 opposite that upon which the roll 95 is mounted. During the limits of 55 height of the pile in which the fanning and feeding members will properly coöperate with the sheets, the position of the roll 95 does not affect the ratchet mechanism, but when the upper sheet of the pile too closely approaches the advancing members, the rod 93 and roll 90 raise the arm 88 sufficiently to completely disengage the pawl from the 60 ratchet-wheel, and, though the crank-disk

continues to rotate, the pawl oscillates idly. When, however, the pile has been lowered, because of the interrupted table-elevation to the necessary extent, the fall of the rod and lever allows the pawl to again engage the 70 wheel and the table-feed is resumed. Obviously this same mechanism will stop any undue rise of the table after the last sheet has been delivered, and thus prevent injury to the apparatus. 75

Sheets are ordinarily separated after being operated upon by the machine to which the feeder delivers into bundles containing some definite number. It is customary, for example, for the operators of ruling machines to separate the successive reams of paper on the table of the feeder by slips of paper, and if they observe when these slips are reached, they can remove the ruled sheets in bundles of five hundred each. It is difficult for the attendant to give this matter the necessary attention, and too many sheets are frequently fed and bundled. The indicating mechanism which will now be described, and which is the subject of my divisional application, Serial Number 178085 filed July 2, 1917, prevents this. 85

Fixed to the shaft 55 just inside one of the standards 10 is an actuating finger or projection 97 coöperating with the teeth of a wheel 98 mounted upon the standard, these teeth being illustrated as twenty in number. At the periphery of the wheel is a projection 99 adapted to engage any one of the teeth of a wheel 100 fixed to rotate in proximity to the wheel 98. The wheel 100 is shown as having twenty-five teeth. Both wheels, while turning loosely on their supports, may be held against too free rotation by any desired means, as by the pressure of springs 101. It will be seen that after the finger 97 has engaged the teeth of the wheel 98 twenty times, the projection 99 will have been moved through three hundred and sixty degrees; so that once in each complete rotation of the wheel 98 it will engage a tooth of the wheel 100, and after five hundred revolutions of the projection 97, or a number corresponding to the sheets in a ream, the wheel 100 will have been advanced a full turn. 100 The use of two wheels thus proportioned is to avoid the employment of a wheel having five hundred teeth, which would be of excessively large diameter. 110

On the wheel 100, here illustrated as being on opposite sides thereof, are projections 102 and 103. The projection 102 engages an arm 104 depending from a lever 105 fulcrumed above the wheel 100, and normally drawn against a stop 106 by a spring 107. Fixed to the lever 105 is a spring-tongue 108 carrying a hammer adapted to contact with a gong or other audible signal device 109. Once in each rotation of the wheel 100, or for five hundred sheets 130

fed, the projection 102 will strike the arm 104, raising the lever from the stop. Then as the projection passes away from the arm, the tensioned lever falling upon the stop 5 will cause the hammer to strike the gong, thus warning the attendant that a ream of paper has been delivered by the feeder. The projection 103 contacts with one arm of a lever 110, the opposite arm of which has an 10 angular end or latch 111 adapted to engage a depression 112 in a wheel 113. This wheel is secured to an oscillatory support or shaft 114 extending across the machine and journaled in brackets carried by the standards 15 10, and has fixed to it an arm 115 upon which is a weight 116 tending to force a pencil or marking device 117 against the top sheet of the pile. The shaft 114 also carries a second arm or setting member 118, which 20 when the pencil is resting upon the sheet lies in the path of the finger 97. When the gong is struck, as a result of the contact of the projection 102 with its actuating arm, the projection 103 also engages the lever 25 110, withdrawing the latch 111 from the wheel-depression. This releases the pencil, causing it to mark the last sheet of the ream, thus giving the attendant a visual indication of the delivery of the predetermined 30 quantity. Consequently upon hearing the gong, he may within a suitable time run over the upper sheets of those operated upon by the machine fed, and on finding the marked sheet will be able to remove the unit- 35 bundle. Upon the next revolution of the finger 97 after the tripping of the latch for the marking device, said finger engages the end of the shaft-arm 118 raising the pencil from the paper and allowing the latch to fall 40 back into the depression, the pencil thus being restored to its normal position.

The table having reached its maximum height and all the sheets having been delivered therefrom, it is necessary to lower it 45 to receive and present for feeding another pile of sheets. Shaft 85 has loosely turning upon it a sprocket-wheel 119 driven by a chain 120 extending over a wheel 121 secured to the shaft 55. The wheel 119 carries 50 one element of a jaw-clutch, the other element 122 of which is splined for longitudinal movement upon the shaft 85 and is engaged by a lever 123 fulcrumed at its upper extremity upon a bracket 124. For the purpose 55 of shifting this lever, a rod 125 sliding through guides on the standards 10 reaches across the machine to the operator's side, and there is provided with a handle. By means of this, when it is desired to return 60 the table to its initial feeding position, the operator may cause the engagement of the clutch-elements, he having first thrown the pawl 83 out of contact with the ratchet-wheel 84. Thereupon the screws 12 are rotated reversely to their feeding movement 65

and the table descends. When the initial position is reached, the table is stopped automatically by the contact of a projection 126 with an angular end portion 127 of the lever 123. This moves the lever outwardly 70 and disengages the clutch, and when the operator has supplied another pile of sheets, he has only to again throw the pawl into co-operation with the ratchet wheel, when the upward travel and feed will be resumed. 75

Having thus described my invention, I claim:

1. An apparatus for feeding sheets from a pile comprising a member provided with a face having a yieldable and a non-yieldable portion, these portions being in simultaneous engagement with a plurality of the sheets, the yieldable portion of the sheet-engaging surface conforming in contour to the edges of said sheets, and means for drawing the sheets from proximity to the member. 80

2. An apparatus for feeding sheets comprising a member having a continuous yieldable face for simultaneous engagement with a plurality of sheets and a face for engagement with a single sheet coincidently with the engagement of the yieldable face, and means for drawing the sheets from proximity to the member. 90

3. An apparatus for feeding sheets comprising a member having a yieldable face for simultaneous engagement with a plurality of sheets and a rigid face for engagement with a single sheet coincidently with the engagement of the yieldable face, and means for drawing the sheets from proximity to the member. 100

4. An apparatus for feeding sheets comprising a member having a yieldable face for simultaneous engagement with a plurality of sheets and a rigid face for engagement with a single sheet, means for drawing the sheets from proximity to said member, and means for adjusting the engaging faces 110 toward and from the sheet-drawing means. 105

5. An apparatus for feeding sheets comprising a member having a yieldable face for simultaneous engagement with a plurality of sheets and a roughened face for engagement with a single sheet, and means for drawing the sheets from proximity to the member. 115

6. An apparatus for feeding sheets comprising a member having a surface for simultaneous engagement with a plurality of sheets and an independent surface for engagement with a single sheet, means for drawing the sheets from proximity to said member, and means for adjusting the engaging faces toward and from the sheet-drawing means. 120

7. In a sheet feeder, a retaining member provided with a face having a portion adapted to conform in contour to the edges 125 130

- of a plurality of the sheets and an independent portion for engagement with another sheet, and feeding means coöperating with the retaining member.
- 5 8. In a feeder, a rotatable shaft, arms projecting therefrom, and fanning and feeding levers fulcrumed on the arms and having operating surfaces of different character.
- 10 9. In a feeder, a rotatable shaft, arms projecting therefrom, fanning and feeding levers fulcrumed on the arms, and means for adjustably securing the arms at different angles about the shaft.
- 15 10. In a feeder, the combination with revoluble arms, of fanning and feeding members movable on the arms and having operating surfaces of different character, and adjustable means for yieldably connecting the arms and members.
- 20 11. In a feeder, a retaining device having an operating face consisting of a member movably mounted upon the retaining device and provided with a portion of yieldable material, and means for adjusting the yieldable portion upon the body of the retaining device in the direction of feed.
- 25 12. In a feeder, a presser-foot having a plate movable thereon, and a screw threaded through the presser-foot and rotatably engaging the plate.
- 30 13. A feeder comprising a retaining member, fanning and feeding members, and means whereby the angular relation of the fanning and feeding members may be varied.
- 35 14. In a sheet-feeder, alternately acting revoluble advancing members for operating upon the sheets, and means whereby one only of the advancing members may be temporarily fixed from its normal position and out of coöperation with the sheets.
15. A feeder comprising a support, alternately acting fanning and feeding members movable thereon, and means for securing the feeding member in a position on the support other than occupied in the normal operation of the feeder.
- 40 16. A sheet-feeder comprising standards, longitudinal supports projecting from the standards, carriers mounted upon the supports, transverse supports held by the carriers, other carriers on the transverse supports, a longitudinal support held in the last-named carriers, and a device coöperating with the sheets and being mounted upon the longitudinal support.
- 45 17. A sheet-feeder comprising standards, longitudinal supports projecting from the standards, carriers mounted upon the supports, transverse supports held by the carriers, other carriers on the transverse supports, a longitudinal support held in the last-named carriers, and devices coöperating with the sheets and being mounted upon the last-named carriers and upon the longitudinal support.
- 50 18. A sheet-feeder comprising standards, longitudinal supports projecting from the standards, carriers mounted upon the supports, transverse supports held by the carriers, other carriers on the transverse supports, a longitudinal support held in the last-named carriers, feeding means mounted upon the last-named carriers, and a retaining member mounted upon the longitudinal support.
- 55 70 75
- Signed at Boston, in the county of Suffolk and State of Massachusetts, this twenty-third day of June 1913.
